US00D602488S

(12) **United States Design Patent**
Jiang et al.

(10) **Patent No.:** **US D602,488 S**
(45) **Date of Patent:** **** Oct. 20, 2009**

(54) **ELECTRONIC BOOK**

(75) Inventors: **Jian-Hong Jiang**, Shanghai (CN);
De-Zheng Lan, Shanghai (CN); **Steven Tseng**, Taipei Hsien (TW)

(73) Assignee: **Inventec Appliances Corp.**, Taipei Hsien (TW)

(**) Term: **14 Years**

(21) Appl. No.: **29/328,683**

(22) Filed: **Dec. 1, 2008**

(51) LOC (9) Cl. **14-02**

(52) U.S. Cl. **D14/341**

(58) **Field of Classification Search** .... D14/496, D14/401, 435, 474, 483, 217, 137, 138, 160, D14/168, 203.1–203.8, 341–347, 138 R, D14/138 C, 138 G, 454, 439, 455, 456, 192, D14/239, 247, 315, 327, 331, 336, 338, 339, D14/374, 393, 394, 399, 400, 429, 432, 125, D14/126, 129, 130, 314; D21/324, 329, D21/330, 331, 333; D18/7; D10/32; 455/556.1, 455/556.2, 11.1, 773, 344–347, 93, 95; 379/433.01, 379/433.07, 433.1, 433.11, 433.12, 433.13; 345/169, 156, 173–179, 905; 348/14.02, 348/790; 341/22; 361/680; 273/148 B; 368/281; 715/727–729, 864; 370/342–344; 369/1, 2, 6, 12; 463/43–47

(57) **CLAIM**

The ornamental design for an electronic book, as shown.

DESCRIPTION

FIG. 1 is a perspective view of an electronic book showing our new design.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets

FIG. 1

FIG. 2

FIG. 3

FIG. 4

FIG. 5

FIG. 6

FIG. 7
